BRUSH AND BROOM

Samuel Steinmetz, Bridgeport, Conn.

Application March 7, 1940, Serial No. 322,653

2 Claims. (Cl. 15—244)

This invention relates to new and useful improvements in brushes and brooms and has particular relation to a novel construction of brushes and brooms and particularly the surface engaging or brushing elements thereof where the brushes and brooms of the invention have a long useful life.

The objects and advantages of the invention will become apparent from a consideration of the following detailed description taken in connection with the accompanying drawing wherein satisfactory embodiments of the invention are shown. However, it is to be understood that the invention is not limited to the details disclosed but includes all such variations and modifications as fall within the spirit of the invention and the scope of the appended claims.

In the drawing:

Fig. 1 is a top plan view showing a brush made in accordance with the invention;

Fig. 2 is a view partly in section and partly in side elevation of the brush of Fig. 1;

Fig. 3 is an end elevational view of the brush but on a smaller scale;

Fig. 4 is a transverse sectional view through the brush showing portions only of the brushing members of Fig. 1;

Fig. 5 is a bottom plan view of a portion of the brush; and

Fig. 6 is a view similar to Fig. 5 but showing the brushing members after they have been treated as will be disclosed.

Referring in detail to the drawing the brush generally designated 10 includes a back 11 in the form of a block or wood although it will be understood that this construction is not essential. Back 11 is provided in its underside with a series of longitudinally extending grooves 12 each receiving a scrubbing or brushing member 13 later to be described in detail. Additionally the back in its forward edge is provided with a groove 14 receiving an edge portion of a strip 15 adapted to be used as a squeegee. Strip 15 is secured with its said edge portion in the mentioned groove by any suitable means as for example, the nails or brads 16.

A metal scraper 17 is secured to the rear edge or to any other convenient part of the back 11 as by means of screws 18. This scraper is to be used for the scraping loose of chewing gum and the like from the surfaces of floors and the like. A recess or socket 19 is provided in the back for the reception of the lower end of a handle (not shown) although it will be clear that some other

arrangement for the securing of a handle to the brush may be made, as convenient.

In its upper surface the back 11 is provided with a longitudinally extending channel 20 and secured to the ends of the back at the ends of said channel are clips 21 fastened as by screws 22. These clips extend above the upper surface of the back and have their upper ends turned inwardly to provide hook-like portions 23 located over the back. Disposed against the upper forward side of the back is an element 24 comprising a piece of sponge rubber.

Element 24 is secured to the back in a manner to permit of the ready removal of the element for replacement or the like and to this end a securing strip 25 is provided. Securing strip 25 comprises an inner elongated element 26 through which nails or brads 27 have been driven and over such strip 26 and the heads of the nails 27 is disposed a metal covering 28 whereby the nails are secured in place and whereby to give the device a finished appearance.

In its end portions the securing strip 25 is provided with openings 29 adapted to cooperate with the hook-like portions 23 of the clips 21 for the purpose of temporarily securing the strip in place. From the drawing it will be understood that the sponge rubber element 24 is disposed against the upper side of the back 11 with a portion of such element overlying the channel 20. Thereafter the securing strip 25 is disposed against such portion of the sponge and pressed downwardly with the opening 29 in one of its ends engaged with the adjacent hook-like portion 23 of one clip 21. Thereafter the securing strip is worked about until its other end is under the hook-like portion 23 of the other clip 21 and the securing strip is then released.

The sponge in attempting to expand to normal size will raise the securing strip so that the opening 29 in its said other end will receive the hook-like portion 23 of the other clip 21. At this time the nails 27 have penetrated through the sponge and the points of such nails are located in the channel 20 as shown best in Figs. 2 and 4. To remove the sponge from the brush the action of applying the securing strip 25 in place is reversed. First one end of the strip is depressed and worked sideways from under the hook with which it has been engaged and then the other end of the strip is shifted in like manner. Thereafter the securing strip is simply removed and the sponge may be removed for washing or for replacement or the like.

All of the brushing or scrubbing members 13

are of the same construction. Each such member comprises a laminated strip taken from an old tire casing. The strips comprise alternate layers of cord and of gum rubber vulcanized together whereby the gum enters between the cords and secures the cords of the respective layers to one another and secures the layers into a mass. In the layers the cords extend diagonally or on a bias and the cords 30 of one layer are arranged to extend crosswise or in directions intersecting the direction in which the cords 31 of the adjacent layers extend. The cords and the rubber gum 32 being vulcanized into a mass a tough resilient structure is provided which is excellent for my purpose.

In making the brush the laminated strip is folded upon itself and its bight portion pressed into one of the grooves 12. This process is repeated until each groove 12 has a member 13 therein and then nails or the like 33 are driven through the back and the folded portions of the members securing the latter to the back. It is noted that the strips have their free end or edge portions extending below the lower surface of the back 11 and such portions of the strips are slitted inwardly from their free ends.

These slits provide tooth-like portions 34 (see particularly Figs. 2 and 5) and it is noted particularly in Fig. 5 that the slits are so made that the teeth of one layer of a folded strip overlap the slits used in making the teeth of the other fold of such strip.

Thus there are no aligned spaces between the teeth of the members and so an even cleaning or scrubbing job may be accomplished using the brush. As the strips are cut from a mass or larger strip of the laminated material the rubber gum when cut draws back from the edge of the cut leaving exposed the ends of the cords. These ends designated 35 in the drawing enter into any brushing operation using the brush as they serve to brush up the very fine dust which otherwise might escape under the teeth or fingers 34.

Fig. 5 shows the teeth 34 the way they appear in a new brush. Fig. 6 shows the appearance of the teeth after the brush has been wet and while yet wet or after they have been treated as will now be described. After the strips have been slit to form the teeth 34 and preferably after the strips have been secured in the grooves or channels in the back the strips are treated by immersion in a solution comprising Epsom salts, vinegar and chemical water. This last is a solution used generally for bleaching and the like and its active ingredients are sodium hypochloride two and three-quarters per cent and sodium carbonate four and one-quarter per cent. The remainder, the inert ingredient is water.

The effect of soaking the strips in such a solution is shown in Fig. 6. There it will be noted that the teeth designated 36 are all twisted out of alignment with the strip portions with which they are integral. The length of the soaking operation depends to some extent on the strength of the solution used as if the solution is made relatively strong the soaking need take place for only a short time whereas when a weak solution is used the soaking must take place for a longer period of time. The action of the solution is expedited when the solution is maintained warm or preferably hot.

In Fig. 6 it is noted that the teeth 36 are curled out of the plane of the remaining portions of the strips and while the drawing shows this curling as substantially uniform in actual practice this is not always the case. The teeth extending to some extent transversely of the brush make a better and for scrubbing purposes a thicker or more solid floor engaging portion for the brush. When the brushing members are wet with water only they twist or distort somewhat as shown but return to substantially the positions of Fig. 5 when they again dry. I attribute this distortion effect to the cords in the structure.

Having thus set forth the nature of my invention, what I claim is:

1. In a brush, a back, a series of brushing members, said members each comprising a vulcanized strip of laminated material including layers of rubber gum and layers of cords, said layers of cords arranged with the cords of one layer transverse of those of the adjacent layer, means securing a longitudinal edge of each of said members to said back, said members slit transversely inwardly from their opposite longitudinal edges whereby such opposite edge portions comprise relatively movable teeth-like portions, and said teeth-like portions being curled out of the planes of the portions of the members by which they are carried by chemical treatment of said members.

2. In a brush, a back comprising a block-like body having a series of grooves opening through its lower side, a series of brushing members each comprising a vulcanized strip including rubber and fibrous layers, each of said members folded upon itself substantially along its longitudinal center line and having its bight portion disposed in one of said grooves, each of said members slit inwardly from its opposite longitudinal edges with the slits in one edge in alternate relation to those in the other edge, and means in said body and passing through the received portions of the members immediately outwardly of their folds and securing the members with their bight portions in said grooves.

SAMUEL STEINMETZ.
